UNITED STATES PATENT OFFICE

157,659

PORTABLE SPACE HEATER

Dave Chapman, Chicago, Ill., assignor to National Die Casting Company, Chicago, Ill., a corporation of Illinois

Application September 11, 1948, Serial No. 148,551

Term of patent 14 years

(Cl. D81—10)

To all whom it may concern:

Be it known that I, Dave Chapman, a citizen of the United States, residing at Chicago, county of Cook, State of Illinois, have invented a new, original, and ornamental Design for a Portable Space Heater, reference being had to the accompanying drawings, forming a part thereof.

In the drawings:

Figure 1 is a front elevational view of a portable space heater, showing my new design;
Fig. 2 is a side elevational view thereof;
Fig. 3 is a rear elevational view thereof;
Fig. 4 is a front perspective view thereof;
Fig. 5 is a top plan view; and
Fig. 6 is a rear perspective view thereof.

I claim:

The ornamental design for a portable space heater, substantially as shown.

DAVE CHAPMAN.
